A. A. KERCH

VALVE LIFTER

Filed June 11, 1921

Inventor,
Andrew A. Kerch,
By Applied, Pool & Sutton Attnys.

UNITED STATES PATENT OFFICE.

ANDREW A. KERCH, OF CHICAGO, ILLINOIS.

VALVE LIFTER.

Application filed June 11, 1921. Serial No. 476,635.

To all whom it may concern:

Be it known that I, ANDREW A. KERCH, a citizen of the United States, and a resident of Chicago, in the county of Cook and State 5 of Illinois, have invented certain new and useful Improvements in Valve Lifters, of which the following is a specification.

This invention relates to improvements in valve spring lifters, a term commonly applied to devices for contracting the valve springs of internal combustion motors in order to facilitate the removal of the valve parts and other work in connection therewith.

15 Valve lifters in general are tools having two forked arms adapted to engage between one end of the spring, and a fixed member or part of the motor, together with means for spreading the arms apart to compress 20 the spring (altho such tools may be also operated by engaging the ends of the springs and drawing the arms together).

The object of the present invention is to provide an improved construction for a tool 25 of the character described, whereby the operations may be accomplished with greater ease and with less expenditure of time and labor.

30 The invention will now be fully described with reference to the accompanying drawings, in which—

Figure 1 is a view in elevation of the valve spring lifter in operative position,

35 Figure 2 is a view in elevation of the same in contracted position,

Figure 3 is a view of the device in longitudinal section taken on line 3—3 of Figure 1, and

40 Figure 4 is another view in longitudinal section taken on line 4—4 of Figure 2.

The valve spring lifter herein described comprises in general two parallel arms 1—1 provided at corresponding ends with forked spring engaging members 2—2, the arms being connected together and moved toward and from each other by means of a linkage 3 embodying the principle of the so-called "lazy tongs", the latter being flexed in opposite directions and held in all positions of flexing by means of a screw shaft 4 connected with the linkage in a manner hereinafter to be described in detail.

55 Each of the arms 1 preferably consists of two bars 5—5 spaced apart laterally and pinned or riveted together at several points thruout their length by pins 6, one of

which serves also as a journal pin for the linkage 3, as will hereinafter be described. The forked end portions 2—2 are preferably separate parts secured between the forward end portions of the bars 5—5 of each arm 1, the same being offset inwardly as at 7 for this purpose. If desired, the forked members may be removably secured to the arms, thus permitting the use of interchangeable members of different sizes for operation on various sizes of valve springs. As clearly shown in Figs. 1 and 2, the ends of the arms carrying the forked portions 2—2 are off-set inwardly and toward each other, so that said forked portions may be brought closer together when the tool is in contracted position, as shown in Fig. 2. This enables the tool to be inserted beneath the spring and in position for lifting the same.

The linkage 3 comprises two pairs of links 8—8 and 9—9, each pair being pivotally connected together midway of their ends at 8^a and 9^a respectively, and the adjacent ends of the links of both pairs being likewise connected together by means of journal pins forming integral extremities of cylindric blocks 10 and 11 respectively located at the points of connection between the pairs of links. Within these blocks 10 and 11 is mounted the screw shaft 4, the same being journalled at its forward end in the block 10, which forms a bearing for the end thereof. A nut 4^a is applied to the outer end of 85 the shaft 4 beyond the block 10, and a collar 12 is pinned to the shaft on the opposite side of said block. Beyond the collar 12 the shaft is threaded thruout substantially one-half the length thereof, said threaded portion engaging the rear block 11. At the free end of the screw shaft is mounted a handle 13.

The pairs of links 8—8 and 9—9 are connected at their free ends with the arms 1—1, two links of each pair being pivotally connected adjacent the forward ends of said arms by means of journal pins 14—14, whereas the ends of the other links of each pair have slidable connection with the rear end portions of said arms thru the medium of pins 15—15 carried by the links, and engaging longitudinal slots 16—16 formed in said arms.

100 From the construction as thus described, the mode of operation of the device is readily apparent to those skilled in the art. If, as

shown in Fig. 1, it is desired to lift the valve spring 17 of the valve of a motor consisting in part of a valve stem 18 having a transverse pin 19 therethru, against which the 5 lower end of the spring normally bears thru the medium of a collar 20, the tool in contracted position is inserted beneath the spring so that one of the forked ends bears upwardly against the collar 20 and the other 10 against a convenient bearing surface at the base of the valve stem. By rotating the screw shaft 4 by means of the handle 13 in a direction to flex the links, the arms would be forced apart, altho maintaining parallel 15 relation to each other. The flexing of the links is manifestly accomplished by forcing the two journal blocks 10 and 11 toward or from each other, or rather, the block 11 engaging the threaded portion of the shaft 20 toward and from the block 10, the latter being non-movable lengthwise with respect to said shaft. The arrangement of the pairs 25 of links 8-8 and 9-9 is such that the same movement is transmitted to the pins 15 and 16 connecting the outer ends of the links with the arms 1-1, the result being a parallel relative movement of said arms. By reason of the location of the screw shaft midway between the arms 1-1 and the nature 30 of the transmission of power to the links, the force is transmitted equally to both arms, moving the same outwardly at the same speed and at the same distance from the axis of the screw shaft. In this manner 35 an equal distribution of the stress thruout the entire structure is obtained, a more balanced action, and a uniform division of the wear to which the parts are subjected.

These features add materially to the continued life and usefulness of the device, and 40 render it more dependable and reliable in use.

Having described a preferred embodiment 45 of the invention, I claim as new and novel in the art to which it relates:

1. A valve spring lifter comprising a pair of parallel arms provided with spring engaging members at one end thereof, an extensible linkage comprising pairs of links each pivotally connected together midway 50 of their ends, and with each other at their adjacent ends, and having pivotal and endwise sliding connection with said arms, and a screw shaft journaled at one point of connection between said pair of links and having threaded engagement at the other point 55 of connection.

2. A valve spring lifter, comprising arms provided at adjacent ends with forked spring engaging members, a parallel movement linkage between said arms, and consisting of pairs of links of equal length, each pair being pivotally connected at midpoints and with each other at their inner ends and with the arms at their outer ends, 60 through the medium of fixed pivotal and sliding pin and slot connections, and a screw shaft journaled at one point of pivotal connection between said pairs of links and screw-threaded connection at the other point 65 of pivotal connection between said pairs of links.

In witness whereof, I hereunto subscribe my name this 8th day of June, A. D., 1921.

ANDREW A. KERCH.
